HYDRAULICALLY ACTUATED SWING BOOM CRANE

Harry Wunsch, Brooklyn, N. Y.

Application January 22, 1947, Serial No. 723,608

4 Claims. (Cl. 212—66)

1

It has been customary to swing a crane boom from side to side by means of mechanism including gears in spite of the objection to gears and the difficulty of keeping the gears and bearings in alinement due to the distortions attendant upon the movement of the supporting frame, and the swinging and bobbing of the boom especially on automotive cranes.

Hydraulic cylinders are cheap and reliable and commonly used for exerting force in various ways and would seem to be suitable for such work. In fact, the use of an hydraulic cylinder and piston has been suggested but a piston rod and crank on the mast tend to stall on a dead center so that a single cylinder is objectionable.

I have overcome this difficulty by the use of two hydraulic cylinders and pistons hinged and connected with the boom either directly or indirectly from the mast and provided with a pump and control valve so that the boom can be swung approximately 90° or more to each side from its center position. This system is capable of continuous hard use with a minimum of interference.

Fig. 1 is a plan view showing one arrangement of two cylinders and pistons for controlling the swinging of a boom on a vehicle such as a portable crane or hoist.

Fig. 2 is a side view of a fragment of a mast and boom with the connected cylinders and pistons.

Fig. 3 is a diagrammatic view showing the arrangement of an hydraulic system for controlling the mast and boom.

Fig. 4 is a side elevation and partial section of a hinge support for the two cylinders.

Fig. 5 has diagrammatic outlines showing the relative positions of the cylinders and their pistons in swinging from one extreme position to another 180° apart.

Fig. 6 shows diagrammatic views of the valve for the lower cylinder in the positions corresponding to the positions of the cylinder in the diagram Fig. 5 immediately above.

Fig. 7 shows diagrammatic views of the valve for the upper cylinder in the positions corresponding to the positions of that cylinder in the diagram Fig. 5 above.

Fig. 8 is a diagrammatic view of a pilot valve controlled system for actuating the valve for one cylinder.

Fig. 9 is a diagrammatic view of a system for controlling the valves for both cylinders actuated directly from the swinging boom or mast.

The mechanism shown and described is especially adapted for use on a motor driven portable crane or hoist in which the frame or chassis 10 serves to support a rotatable mast 11 to which the boom 12 is hinged for instance by the hanger 13 which is a part of or carried by the mast.

The cylinders 14 and 15 are pivoted in this case on a common post or pin 16 which is sup-

ported in arms 17, 18 and 19 in any suitable manner.

Pistons of any suitable type have rods such as 20 and 21 hinged to crank arms 22 and 23 respectively, which are connected to or formed as a part of the hanger 13 which carries the boom.

It will be seen that cylinder 15 is mounted to swing in a plane above cylinder 14. This is necessary in order that the cylinders and their pistons and respective crank pins can clear each other as the mast is rotated from one extreme to the other as indicated in the diagram of Fig. 5.

A tank 25 contains a supply of suitable liquid such as oil which is forced through the system 15 by a power driven pump 26 and its flow controlled by a 3-way manually actuated valve 27 usually spring centered. The pump may be of any suitable type which will provide fluid under pressure such as a rotary vane pump. Quick acting "over center" cam tripped valves A and B are connected between the ends of the cylinders and to the load pipe lines L1 and L2 which are connected to valve 27. With the valve 27 in the position of Fig. 3 and the pump actuating, liquid 20 will be forced through the pipe line L1 and the valves A and B in such a manner as to rotate the mast and boom in an anti-clockwise direction. By turning the valve 27 so that the pump discharge will pass through line L2, the rotation 25 of the mast and boom will be reversed. A check 30 valve 29 may be interposed between the pump 26 and valve 27.

Fig. 6 shows the positions a, b, c, d, and e of the valve A with respect to the lines L1 and L2 35 and the head end and crank end of the cylinder 14 corresponding to the positions a, b, c, d, e of the cylinder shown above each valve sketch in Fig. 5, and Fig. 7 shows the corresponding positions a, b, c, d and e of the valve B with respect to the pipe 40 lines L1 and L2 and the head and crank ends of the cylinder 15. In position d of valve A for cylinder 14 the valve A is just snapping over from position c to position e and in position b of valve B for cylinder 15 the valve B is just snapping over from position a to position c.

It will thus be seen that high pressure liquid 45 may be applied to the system through either pipe L1 or L2 and returned to the tank 25 through the reverse line L2 or L1 depending upon the position of valve 27. The crank connections are set at such an angle to each other and with respect to the mast as an axis, that when one cylinder goes through dead center the other is operating 50 at or near a maximum radius. When a cylinder passes dead center it automatically trips its individual valve (A or B) which reverses the pressure from the head end to the crank end of the cylinder or vice versa depending upon the direction 55 of rotation. The automatic trip valve may be of any suitable type either mechanical or an 60

electrically controlled solenoid or a hydraulic pilot valve.

The cylinders may be hinged at any convenient location either on a common axis or separately, depending upon the layout of the other mechanism. The location of the crank arms 22 and 23 with respect to the direction of application of pressure by the piston rods should be such that when one piston is pressing on its crank pin at dead center the other piston is pressing on its crank pin at its most effective angle. This means that with the cylinders mounted on a common axis as shown, the crank arms would be arranged at approximately right angles to each other. This relation of the crank arms however may be varied according to the location of the pivots of the cylinders so long as the possibility of dead center effect is avoided as above pointed out. The direction of motion of the mast and boom is controlled by simply shifting the valve 27—the rest of the operation being automatic. The cylinders being double acting are each effective.

There are several ways in which the over the center action can be effected. Fig. 8 shows a diagram of a pilot valve system. Valve B is fed from valve 27 through pipes L1 and L2 and controls the liquid pressure to the opposite ends of cylinder 15. The actual tripping action is effected by a standard pilot valve 30 which obtains pressure from the pump 26 which is always available because the pilot valve 30 is connected between the pump 26 and the spring loaded check valve 29. The pilot valve 30 controls the main valve B which actually handles the main body of fluid to the cylinder 15. Valve A is actuated in a similar manner to control cylinder 14. The arrows in Fig. 8 indicate connections to the valve A and its pilot valve (not shown). Valve 27 is actuated by hand.

Another method of obtaining the over the center action is shown in the diagram of Fig. 9. Valve 27 of course is actuated by hand and directs the liquid pressure thru pipe L1 or L2 to valves A and B depending upon which direction of rotation of the boom is desired. The "over the center" action of valve A is effected by the rod 31. This rod is connected by the rocker 32 to the valve rod 33 and is actuated by another rocker 34. A projection 35 rotated on or by some part of the mast 11 or boom tilts the rocker 34. The other end of rocker 34 engages a slide 36 on rod 31 which is compressed between two springs 37, 38 on the rod 31. Spring pressed roller 38 engages a notch 39 in rod 31 and thus resiliently holds the rod and connected parts in a given position. When the rocker 34 is tilted clockwise sufficiently to compress the upper spring and overcome the pressure of roller 38 in notch 39, the rod will jump so that roller 38 will be retracted and will drop into notch 40—thus moving the valve stem 33.

The over center snap action of valve B is similarly effected by a projection 35' carried by or mounted on the mast or boom, actuating the stem of the valve as shown at the right side of Fig. 9. In this case the stem or rod 41 of valve B is actuated from the projection 35' on the mast by the rocker 42. It should be understood that while this invention permits turning the mast and boom 180° or more there doubtless may be cases where it is not necessary to provide the full turn.

I claim:

1. A hydraulically actuated swing boom crane comprising a rotatable supporting means, a boom

carried by said means, said rotatable supporting means including two crank arms extending radially from the axis of said supporting means in planes diverging at an acute angle to each other, a hinge connection at the outer end of each arm, said hinge connections being movable in parallel planes spaced about from each other vertically, and hydraulically actuated means for rotating said supporting means including two cylinders, means for supporting said cylinders to turn in said respective parallel planes, a piston in each cylinder having a piston rod connected to its respective hinge connection and hydraulic means for actuating said pistons and turning said supporting means.

2. A hydraulically actuated swing boom crane comprising a rotatable supporting means, a boom carried by said means, said rotatable supporting means including two crank arms extending radially from the axis of said means in planes diverging at an acute angle to each other, a hinge pin at the outer end of each arm, said hinge pins being movable in parallel planes spaced apart from each other vertically, and hydraulically actuated means for rotating said supporting means including two cylinders mounted on a common post to turn in said respective parallel planes, a piston in each cylinder having a piston rod connected to its respective hinge pin, and hydraulic means for actuating said piston and turning said supporting means.

3. A hydraulically actuated swing boom crane comprising a rotatable supporting means, a boom carried by said supporting means, said rotatable supporting means including two crank arms extending radially from the axis of said means in planes diverging at an acute angle to each other, a hinge connection at the outer end of each arm, said hinge connection being movable in parallel planes spaced apart from each other vertically, hydraulically actuated means for rotating said supporting means through approximately at least 90° to the right and left from a central position including two cylinders, means for supporting said cylinders to turn in said respective parallel planes, a piston in each cylinder having a piston rod connected to its respective hinge connection and a pump and valve system for actuating said pistons including snap action mechanism for carrying each cylinder over the dead center while the boom is turning.

4. A hydraulically actuated swing boom crane comprising a rotatable mast, a yoke fastened to the mast, a pair of arms on said yoke diverging from each other on different horizontal planes, a pair of cylinders hingedly supported at one end on the same horizontal planes as said arms, hydraulically actuated piston rods protruding from the cylinders, hinged connections between the protruding ends of the piston rods and the ends of the arms of the yoke for rotating the mast in opposite directions and a boom fastened to said yoke for rotation with the mast.
